COMPOUND SHOE CONSTRUCTION FOR FLOATING ROOF SEALING MECHANISM

John H. Wiggins, Woodside, Calif.

Application August 3, 1955, Serial No. 526,117

1 Claim. (Cl. 220—26)

My invention relates to improved sealing mechanisms for a floating roof for tanks employed for storing oil and the like, and which comprises an annular shoe arranged in sliding sealing engagement with the side of the tank with the bottom edge portion of the shoe projecting into the liquid in the tank on which the roof floats, and is concerned more particularly with the provision of a compound shoe structure including inexpensive flexible, strong material in the major portion of the sliding shoe which is above the liquid, and at the lower liquid contacting section part of the shoe providing a corrosion-resistant structure, the lower corrosion-resistant section being connected in a gas-tight manner to the upper section of the sliding shoe.

It is a general object of the invention to provide a sealing mechanism for a floating tank roof structure in which the shoe is of two-part construction.

Another general object of the invention is to provide a compound shoe in which a corrosion-resistant section of the sliding shoe is provided adjacent to the liquid level within the tank to increase the life of the sliding shoe.

Another object of the invention is to provide a seal structure of the above character in which a lower section of the corrosion-resistant material is connected to an upper section of conventional steel by a gas-tight joint which includes means for securing the outer periphery of a fabric seal between the sliding shoe and the floating roof.

Another general object of the invention is to provide a sliding shoe for a seal structure in a floating roof in which the circumferential limberness of the shoe is maintained so as to conform readily to irregularities in the circumference of the tank to maintain an effective sealing engagement with the tank, and also to provide satisfactory anti-corrosion characteristics of the portion of the shoe contacting or submerged in the liquid in the tank.

Other objects and advantages of the invention will be apparent from the following description of certain preferred embodiments, taken in connection with the accompanying drawings, in which:

Figure 1 is a fragmentary sectional view of a sealing mechanism for floating roofs and embodying my invention.

Figure 2 is an enlarged fragmentary view of a portion of Figure 1.

Figure 3 is a vertical sectional view of a sealing mechanism for floating roofs showing another preferred form of my invention.

One of the principal characteristics of sliding shoe seals of a cylindrical character in conjunction with floating roof tanks, is that the shoe in order to serve its purpose satisfactorily, must maintain substantial contact with the tank around its periphery, conforming to irregularities around the circumference of the tank, and at the same time provide sufficient strength structurally to support loads imposed by snow, freezing, and accidental causes. This problem has led to the conventional procedure of

2

using thin, inexpensive steel plate about $\frac{1}{16}$ " thick, for this sliding shoe. The principal difficulty with the thin, inexpensive steel structure for this sliding shoe is the fact that in all oils, the area of maximum corrosion on the steel is around the lowermost portion of the shoe within the tank where contact with air and vapor occurs at the oil surface, and the corrosion at this point occurs several times as rapidly as on any other part of the shoe, this being particularly true in corrosive oils. Because of the size of the shoe and the large circumference of the tanks in which it is used, the fabrication of the entire shoe of a corrosion-resistant material is prohibitive because of the expense.

In accordance with my invention, in a floating roof seal structure, a compound shoe structure is provided in which a lower part or secondary section having corrosion-resistant qualities is provided, and in which an upper part or primary section is made of thin, inexpensive steel for the necessary strength and flexibility in conforming to the walls of the tank. Preferably also, the shoe is made in two parts which overlap each other, and the fabric seal is placed between the lapped portions and clamped securely in place in a gas-tight fashion. This provides an economical and satisfactory method of attaching the outer edge of the fabric seal to the sliding shoe structure.

Referring to the drawings, particularly Figures 1 and 2, there is shown a fragmentary section of a cylindrical wall 1 of a storage tank of the kind used extensively throughout the oil industry for storing oil and other volatile liquids. Within the tank 1, a floating roof structure is provided of the conventional type, comprising an outer rim 9 secured and extending upwardly from a bottom deck 10, to a top deck 11. To seal the space between the floating roof structure and the outer wall, a seal mechanism is provided including a sliding cylindrical shoe 2 comprising a primary upper section 2a extending through the major portion of the height of the shoe, and a lower secondary section 2b at the lower portion of the tank adjacent to liquid level 5.

The shoe 2 is connected to the rim 9 of the roof by an annular flexible gas impervious curtain or fabric seal 4, which is clamped to the upright wall 9 of the roof by a seal bar 7 and a plurality of nut and bolt connections 8 spaced thereabout providing a gas-tight joint. The outer periphery of the fabric seal 4 is clamped between an offset portion 3 of the upper primary shoe section 2a and the overlapping portion of the lower secondary shoe section 2b by a plurality of suitable nut and bolt fastenings 6, this connection providing a gas-tight joint at the outer periphery of the fabric seal 4.

Referring to Figure 2, the upper section 2a is provided at each nut or stud 6 with a depressed portion having a frusto-conical surface 22, and the lower section 2b of the shoe is provided with a similar mating depressed portion having a frusto-conical surface 23 in which the head of the bolt 6 is seated. The fabric seal 4 is apertured and clamped between these frusto-conical surfaces.

At a plurality of points about the periphery of the floating roof structure, pressure and supporting rods 13 are provided, each having a channel piece 12 at the outer end thereof. Each rod 13 has sliding engagement within a pipe 14 in the roof wall or rim 9. A washer 15 is provided on the rod 13 as an abutment for a compression spring 16 engaged between the washer 15 and the end wall 14a of the pipe 14.

Preferably, the lower section 2b of the overlapping sections of the sliding shoe is corrosion-resistant, either by being constructed of thicker steel so as to resist corrosion by the amount of material present or a suitable corrosion-resistant material of thinner section is provided so as to be capable of conforming to the irregularities

within the tank. The lower secondary section 2b may be constructed of thin, stainless steel as the preferred anti-corrosion material, or a suitable anti-corrosion plastic sheet, or of a steel plate coated with plastic.

By providing a compound shoe of two overlapping sections, not only is there provided a suitable point of anchorage for the outer periphery of the fabric seal 4, but there is provided a lower section which is a minor fraction of the total area of the shoe so that it can be constructed economically of expensive corrosion-resistant material, and substantially increase the life of the sliding shoe within the tank at the point of greatest corrosive activity within the tank, i. e., at the liquid level therein.

Referring to Figure 3, there is shown a sealing structure for the floating roof, in which the flexible fabric seal 4 is attached between the upper edge of the upright rim 9 of the floating roof and the upper portion of the shoe 2 by means of suitable seal bars 7a in a conventional manner. The offset edge 3 of the upper section 2a of the shoe is secured directly to lower section 2b. Otherwise the construction is identical with that described in connection with Figure 1.

It will be noted that in each of the modified structures shown and described herein, the structural arrangement provides for a corrosion-resistant material at and adjacent to the liquid level in the tank so that maximum life can be obtained at this weakest region of the shoe. Also where a fabric seal is employed immediately adjacent to the liquid level, the provision of the compound shoe structure enables an advantageous securing of the outer edge of the seal, without the use of the conventional seal bar.

While I have shown and described certain embodiments of the invention, it will be apparent that the invention is capable of variation and modification from the form shown so that the scope thereof should be limited only by the scope of the appended claim.

I claim:

In a sealing mechanism for a floating roof for a sub-

stantially cylindrical upright tank for storing a liquid having corrosive characteristics, a substantially cylindrical compound sealing shoe assembly disposed about the periphery of said roof and spaced radially outwardly therefrom, said sealing shoe assembly including a primary upper shoe section and a secondary lower shoe section each substantially cylindrical in shape and each in intimate sliding engagement through the major portion of its height with the inner wall surface of said tank, said upper shoe section and said lower shoe section respectively constituting major and minor portions of the total height of said sealing shoe assembly, means carried by said roof and connected to said upper shoe section for supporting and maintaining said upper shoe section at a substantially constant elevation with respect to said roof and totally above the liquid in said tank, said upper shoe section being formed of mild steel and the lower edge thereof terminating above and adjacent to the liquid in said tank so that said upper shoe section is totally out of direct contact with the liquid in said tank and is thus free of the major corrosive actions thereof, said lower shoe section being rigidly secured to and supported solely by said upper shoe section and depending therefrom and projecting into the liquid in said tank, said lower shoe section being formed of stainless steel so that it is not damaged by the normal corrosive actions of the liquid in said tank, means for sealing in gas-tight relation the lower portion of said upper shoe section and the upper portion of said lower shoe section, and a flexible gas-tight curtain extending between and sealed in gas-tight relation with said roof and said sealing shoe assembly.
